CYRUS J. PARKER, OF PORTLAND, OREGON; MARY E. PARKER, EXECUTRIX OF SAID CYRUS J. PARKER, DECEASED, ASSIGNOR TO IRON FIREMAN MANUFACTURING COMPANY, OF PORTLAND, OREGON, A CORPORATION

TUYÈRE

Application filed May 16, 1927. Serial No. 191,609.

This invention relates generally to grates for burning coal, and particularly to grates for end feed stokes.

The first object of this invention is to provide an exceedingly simple and efficient type of tuyère for use in connection with end feed stokers in which the coal is fed upwardly past the tuyère by means of a screw (not shown).

The second object is to produce a tuyère in which the openings will not be subject to clogging on account of the special form of tuyère opening employed.

The third object is to so construct the tuyère element that it will lend itself to easy assembling and will not be apt to burn out on account of the cooling action of air on the under side.

These, and other objects, will become more apparent from the specification following as illustrated in the accompanying drawings, in which:

Figure 1 is a front elevation of a tuyère element of which Figure 2 is a vertical section taken along the line 2-2 in Figure 1. Figure 3 is a horizontal section taken along the line 3-3 in Figure 2. Figure 4 is an enlarged section through the tuyère element slots taken along the same plane as is Figure 2 and showing the tendency of coal and ash to fill the tuyère slots. Figure 5 is a perspective view of a number of tuyère units showing their relation to the coal bed and showing the supporting members for the tuyère element.

Similar numbers of reference refer to similar parts throughout the several views.

Referring in detail to the drawings, the tuyère element itself consists of an upright member 10 whose side 11 is vertical and whose side 12 slopes upwardly from its lower corner 13. On the sides of the member 10 are formed the lateral projections 14. The projections 14 are made thicker at the middle than at the ends so that the spaces 15 between them are centrally constricted. Such structure will produce a Venturi effect on the air when the elements are assembled to form a tuyère (as shown in Figure 5).

At the bottom of the member 10 is formed

a pair of laterally extending lugs 16 whose over-all width is the same as the members 15. The top side 17 of the tuyère element is also carried out to the full width of the members 14 and is preferably provided with a groove 18 for the reception of the down-turned flange 19 of the grate bar 20. The member 10 has an outwardly projecting portion 21 from which extends an upright portion 22 which connects with the under side 60 of the portion 17 containing the groove 18.

The under side 23 rests upon the T bar 24 and the inwardly projecting tongue 25 locks under the flange 26 of the fuel feeding trough 27 (shown in part) which contains the feed screw (not shown).

The operation of the device is as follows: When coal is fed upwardly by the worm (not shown) it naturally moves outwardly under the pressure of the worm and, due to the expansion of the coal caused by the heat being generated above same, causes particles of coal 28 and ashes 29 to fall into the discharge ends of the Venturi openings, where it would remain were it not for the fact that a strong 75 current of air is constantly issuing from these openings.

I am aware that many different forms of tuyère elements have been constructed in the past; it is therefore not my intention to 80 cover such devices broadly but merely intend to cover such forms and modifications thereof as fall fairly within the appended claim.

I claim:

A tuyère member adapted to be arranged in an upright position to form a section of the upper portion of a fuel retort of an underfeed stoker, and having when in such position, two upright portions, spaced apart, one of which is wider than the other, a narrow 90 portion connecting the lower ends of said portions and a top portion of the same width as said wider portion connecting the upper ends of said portions, said wider portions having a continuous fuel-engaging surface, 95 the outer portion of the top of the member being provided with a groove and the bottom with a retaining lug, said wider upright portion being provided in its lateral edges, 100 with channels extending from surface to sur-

face and flaring from their middle portions to said surfaces, the upright fuel-engaging face being slightly inclined outwardly and upwardly and the fuel-engaging face of the 5 top being inclined downwardly and outwardly.

CYRUS J. PARKER.
